(74) Attorney, Agent, or Firm—Thomas J. Nikolai; Nikolai & Mersereau, P.A.

(21) Appl. No.: **29/156,152**

(57) **CLAIM**

(22) Filed: **Feb. 26, 2002**

The ornamental design for a drive motor mount for clamshell lathe, as shown and described.

(51) **LOC (7) Cl. 15-01**

DESCRIPTION

(52) **U.S. Cl. D15/1**

FIG. 1 is a side perspective view of a drive motor mount for clamshell lathe showing my new design;

(58) **Field of Search D15/1, 5; 392/478,**
392/480, 483-485; 290/52

FIG. 2 is a left end view thereof;

(56) **References Cited**

FIG. 3 is a right end view thereof;

FIG. 4 is a top plan view thereof; and,

FIG. 5 is a bottom plan view thereof.
